US0D1109923S

(12) **United States Design Patent** (10) **Patent No.:** **US D1,109,923 S**
(45) **Date of Patent:** **** Jan. 20, 2026**

(54) **EYELINER**

(71) Applicant: **Youb Kim**, Siheung-si (KR)

(72) Inventor: **Youb Kim**, Siheung-si (KR)

(**) Term: **15 Years**

(21) Appl. No.: **29/854,862**

(22) Filed: **Sep. 28, 2022**

(30) **Foreign Application Priority Data**

Mar. 31, 2022 (KR) 30-2022-0012721

(51) **LOC (15) Cl.** **28-02**

(52) **U.S. Cl.**

USPC **D28/7**

(58) **Field of Classification Search**

(57) **CLAIM**

The ornamental design for an eyeliner as shown and described.

DESCRIPTION

FIG. 1 is a perspective view of an eyeliner showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view of the eyeliner of FIG. 1; and,

FIG. 7 is an enlarged bottom plan view of the eyeliner of FIG. 1.

The broken lines in the figures illustrate portions of the eyeliner that form no part of the claimed design.

1 Claim, 7 Drawing Sheets
